CLOCK

Charles Hilaire Henri Rodanet, Neuilly-sur-Seine,
 France, assignor to Societe Anonyme: Eta-
 blissements Ed. Jaeger, Levallois-Perret Seine,
 France

Application August 14, 1950, Serial No. 11,748
 In France March 8, 1950

Term of patent 7 years

(Cl. D42—7)

To all whom it may concern:

Be it known that I, Charles Hilaire Henri Rodanet, a citizen of the French Republic residing at 23, villa Madrid, Neuilly-sur-Seine, Seine, France, have invented a new original and ornamental Design for a Clock, of which the following is a specification, reference being had to the accompanying drawings, forming part thereof.

In the drawings:

Fig. 1 is a front elevational view of a clock showing my new design, the solid black indicating the contrastingly colored narrow rim and background plate.

Fig. 2 is a rear perspective view of the clock, with a portion thereof broken away for the purpose of better illustrating the narrow rim, the three transparent disks having astronomical

symbols thereon, and the background disk.

I claim:

The ornamental design for a clock, as shown and described.

CHARLES HILAIRE HENRI RODANET.
